Cincinnati, Ohio, a corporation of Ohio

Application June 2, 1939, Serial No. 277,040

19 Claims. (Cl. 51—95)

This invention relates to machine tools and more particularly to improved transmission and control mechanism for cylindrical grinding machines.

One of the objects of this invention is to provide improved table traversing mechanism and control means for a cylindrical grinding machine.

Another object of this invention is to provide improved means for interlocking the traversing mechanism and the infeed mechanism of a cylindrical grinding machine so that undesirable simultaneous operation for both mechanisms will be prevented.

A further object of this invention is to provide an improved automatic infeed mechanism for a cylindrical grinding machine which is sufficiently flexible that the rapid traverse part of the infeed movement may be varied at will to reduce the time of the feeding movement.

Other objects and advantages of the present invention should be readily apparent by reference to the following specification, considered in conjunction with the accompanying drawings forming a part thereof and it is to be understood that any modifications may be made in the exact structural details there shown and described, within the scope of the appended claims, without departing from or exceeding the spirit of the invention.

Referring to the drawings in which like reference numerals indicate like or similar parts:

Figure 1 is a front elevation of a grinding machine embodying the principles of this invention.

Figure 2 is a section through the machine shown in Figure 1 as viewed on the line 2—2 showing the infeeding mechanism for the wheel head.

Figure 3 is a section on the line 3—3 of Figure 1, showing the control lever in a partially advanced position.

Figure 4 is a section on the line 4—4 of Figure 3.

Figure 5 is a detail elevational view partly in section to show the adjusting mechanism for the variable stop of the infeed control lever.

Figure 6 is a detail section of the rapid traverse infeed stop.

Figure 7 is a detail section through the end of the reverse valve.

Figure 8 is a diagrammatic view of the hydraulic control circuit of the table traversing mechanism.

Figure 9 is a diagram of the hydraulic control circuit for the infeed mechanism.

Figure 10 is a detail view of the yieldable stop for the table traverse control lever.

Referring to Figures 1 and 2 of the drawings the reference numeral 10 indicates the bed or main support of the grinding machine upon the top of which is formed, as shown in Figure 2, a flat guideway 11 and a V-guideway 12 for supporting and guiding the work table 13. This table is provided with a conventional headstock, indicated generally by the reference numeral 14, including a motor 15 for driving the face plate 16. In addition, a tailstock 17 is provided, having a quill 18 carrying the tailstock center 19 as shown in Figure 9. This quill, in addition to being manually controlled by the levers 20 and 21 shown in Figure 1 through the usual conventional means, is also adapted to be hydraulically retracted by a piston 22, slidably mounted in a cylinder 23, through a centrally pivoted lever 24. A grinding wheel 25 is rotatably journaled on a wheelhead 26 which is guided on the bed for movement toward and from the work. The head 26 carries a prime mover 27 which is belt-connected for effecting rotation of the grinding wheel. Referring to Figure 8, the table 13 is provided with depending brackets 28, which support a cylinder 29 for movement with the table. A piston 30 is contained within the cylinder and connected by piston rods 31 and 32 to fixed aprons mounted on opposite ends of the bed in a conventional manner.

Thus, with the piston rod and piston fixed, the admission of hydraulic pressure to opposite ends of the cylinder is effected through the piston rods which are made hollow and provided with cross bores 33 adjacent opposite sides of the piston.

The depending brackets 28 also carry a rack 34 which serves as means for driving the table manually through the hand wheel 35. This hand-wheel is attached to the end of a pinion 36 which meshes with a spur gear 37, the spur gear having a co-axial pinion 38 which drives the rack through an intermediate idler 39. In order to prevent rotation of the hand wheel during power actuation of the slide, a piston 40 slidably mounted in a cylinder 41 is axially aligned with the pinion 38 for shifting the same to the left, as viewed in Figure 8, out of engagement with the idler gear 39.

Power traverse of the table is controlled by a start and stop control lever 42 which is mounted on the front of the machine as shown in Figure 1 and integrally connected to a start and stop control valve which has a fixed sleeve 43 and a

rotatable plunger 44. This plunger has various control portions throughout its length, and to facilitate understanding of the operation of this valve, a series of sections through the valve are shown in Figure 8 and indicated by the reference numerals 45 to 52 inclusive, it being understood that the outside portion is all part of the fixed sleeve and that the center portion in each section is all part of the valve plunger and integral with the lever 42 whereby when the lever 42 is rotated counterclockwise as viewed in Figure 8 to its "run" position the center portion of each of the sections will be rotated through the same angle.

The opposite ends of the table motor are connected by channels 53 and 54 to ports 55 and 56 of the start and stop control valve, the ports being shown in sections 45 and 46 of this valve. These sections also have ports 57 and 58 which are connected to the pressure supply line 59.

This line is supplied with fluid pressure by a pump 60, which has an intake 61 through which fluid is withdrawn from a reservoir 62. It will be noted that in the stop position of this valve that both ports 55 and 56 are connected to the pump whereby pump pressure will exist in opposite ends of the cylinder 29 maintaining the same full of oil, thereby preventing admission of air to the system, but at the same time not interfering with manual traverse of the table by the wheel 35 since the oil in one end of the cylinder will be bypassed through the valve into the other end whenever the hand wheel is rotated.

When the lever 42 is thrown to its running position the arcuate grooves 63 and 64 will connect ports 55 and 56 to ports 65 and 66 respectively and thereby through channels 67 and 68 to ports 69 and 70 of a reversing valve, indicated generally by the reference numeral 71.

The reversing valve has a plunger 72 which is power shifted from one end of the valve housing to the other by hydraulic means, which is controlled by a pilot valve, indicated generally by the reference numeral 73. The pilot valve has a plunger 74 which is mechanically connected by a crank 75 to the trip rod 76, this rod terminating in the trip lever 77 adjacent the side of the table as indicated in Figure 1.

Since the plunger 72 of the reversing valve has only two positions, the pressure port 78 of this valve will be connected at all times to either port 69 or 70 by means of annular grooves 79 and 80 respectively.

With the plunger 72 in the position shown, ports 78 and 69 are interconnected, and fluid pressure will flow through channel 87, port 85, groove 63, port 55 and channel 53 to the left end of cylinder 29, causing movement of the table 13 toward the left. Fluid from the other end of the cylinder will return through channel 84, port 86, groove 64, port 66, channel 68 to port 70 of the reversing valve. The latter port is interconnected by the annular groove 80 to exhaust port 81. Should the plunger 72 be shifted upward as viewed in Figure 8 to its other position the pressure port 78 would be connected to port 70, and port 69 would be connected to the exhaust port 82.

The rate of table traverse is controlled by throttling the exhaust fluid from the table motor rather than throttling the inflow as is done in many cases. The traverse rate throttle valve is indicated by the reference numeral 83. Means are provided in the pilot valve for alternately connecting the exhaust ports 81 and 82 of the

reverse valve with the throttle valve 83 in accordance with the direction of table movement, so that one throttle valve will serve to control the rate in both directions.

5 This is accomplished by connecting ports 81 and 82 to ports 84 and 85 of the pilot valve by means of channels 86 and 87 respectively, and providing annular grooves 88 and 89 on the pilot valve plunger for alternately connecting ports 84 and 85 to port 90. The latter port is connected by channel 91 to the intake port 92 of the throttle valve 83. This valve has an exhaust port 93 which is connected to the return line 94 that conveys the fluid back to the reservoir 62. A low pressure relief valve 95 is serially connected in the channel 94 for maintaining the system full of oil.

As the table nears the end of its stroke, a dog 96 suitably positioned on the table starts rotation of the trip lever 77 and thereby through the mechanical linkage previously explained starts longitudinal movement of the pilot valve plunger 74. The pilot valve has a pressure port 97, and a pair of ports 98 and 99 which are connected to opposite ends of the reversing valve for alternately delivering pressure thereto to effect power shifting of the plunger 72. Attention is invited to the fact that the pilot valve plunger has a spool 100 which is larger in diameter than adjacent spools 101 and 102 whereby after the spool 100 passes pressure port 97 the admittance of fluid pressure behind the spool 100 will complete the shifting of the plunger 74 due to the difference in pressure on the opposing ends of adjacent spools.

35 The spool 100 reciprocates in the enlarged bore 103 and the length of this bore determines the length of movement of the plunger 74. The pilot valve plunger is thus self-actuating after it passes a mid-position.

With the pilot valve plunger 74 in the position shown in Figure 8 in which the pressure port 97 is connected to port 98, the fluid has passed through channel 104, the lower end 105 of check valve 106, to port 107 of a tarry valve 108. This valve has a rotatably adjustable plunger 109 in the periphery of which is cut a V-shaped groove 110 for varying the resistance of port 107 and thereby the rate of flow through the valve to port 111. This port is connected by channel 112 to annular groove 113 formed in the sleeve of the reversing valve. This groove communicates with two spaced ports 114 and 115.

55 The channel 112 has a branch line 116 which is connected to the upper end 117 of the check valve 106 whereby upon upward shifting of the reverse valve plunger 72, the returning fluid will build up pressure in channels 112 and 116 due to the resistance of the tarry valve and shift the plunger 118 of the check valve against the resistance of spring 119 and thereby uncover the exhaust port 120. Since this port is connected to the return channel 94 the fluid exhausting from the reversing valve will be returned to reservoir.

60 When the pilot valve plunger 74 moved downward past its mid-position under the action of the table dog, the pressure port 97 will be connected to port 99 and fluid will flow through channel 121, the lower end 122 of check valve 123, channel 124 to port 125 of the tarry valve 126. This valve also has a rotatably adjustable plunger 127 in which is cut a V-shaped groove 128 for variably determining the resistance of port 125.

65 The fluid passing through this valve continues

through channel 128' to the annular groove 129 formed in the lower end of the reversing valve sleeve. This groove also has a pair of ports 130 and 131.

Each end of the reversing valve plunger 12 is constructed as shown in Figure 7. An annular groove 132 is cut in the periphery of the plunger to form a spool 133 of a width substantially equal to the width of ports 114 and 130, so that upon movement of the plunger from one extreme position to the other, the spools 133 will completely close ports 114 and 130 in the middle of the stroke of the plunger. A cross bore 134 is drilled in the bottom of the groove 132 to intersect a longitudinal bore 135.

The latter bore has an enlarged portion 136 which is threaded at the end to receive a plug 137 and thereby form a chamber in which is mounted a spring pressed ball check 138 for normally closing the end of the bore 135. The plug 137 has a small axial bore 139 formed therein whereby fluid entering the cross bore 134 and passing the ball check 138 may reach the end chamber 140.

The manner of operation is as follows:

A table dog such as 86 rotates the trip lever 77 and thereby moves the pilot valve plunger 74 toward its mid-position. The tapered spool 142 on the pilot valve plunger gradually closes port 90, thereby restricting the exhaust flow from the table cylinder 29 which results in deceleration of the table. When the pilot valve plunger reaches its mid-position the port 90 will be completely closed and the table movement should cease. During this same time the spool 100 has moved to a central position with respect to the pressure port 97. Although the momentum of the parts will no doubt be sufficient to carry the pilot valve plunger slightly beyond its midposition so that the hydraulic pressure at port 97 may complete the shifting movement, it will be apparent that it is possible with the spool 142 closing port 90 and spool 100 closing port 97 for the parts to be in equilibrium and the table at rest, whereby automatic reversal could not be completed. In order to insure against such a condition happening the opposite ends of the table cylinder are connected by bleeder pipes 143 and 144 to ports 145 and 146 respectively of the pilot valve. The pilot valve plunger is provided with an annular groove 147 in which is drilled a cross bore 148 intercommunicating with an axial bore 149. The axial bore 149 has free communication with the atmosphere whereby fluid passing through these interdrilled passages may freely exhaust to reservoir.

When the pilot valve plunger reaches its mid-position the ports 145 and 146 are both in communication with the groove 147 although each port is about half closed. This permits the fluid in that end of the cylinder which is not connected to pressure to bleed to reservoir sufficiently to continue the movement of the table the small amount necessary to carry the pilot valve past its midposition. It will now be apparent that the spool 142 on the pilot valve during movement of the latter to its midposition acts as means to decelerate the movement of the table.

After the pilot valve is fired by hydraulic pressure, the port through which the bleeding occurred is completely closed and the movement of the table stopped. Pressure fluid will now be connected to port 99 of the pilot valve and there- 70 through the tarry valve 128 to the annular

groove 129 of the reversing valve. Due to the high resistance of port 131 the fluid will flow through port 130 and annular groove 132 in the reversing valve plunger to the ball check 138 which will open under pressure, thereby permitting the fluid to continue through passage 139 to space 141. The pressure acting in this space will cause upward movement of the reversing valve plunger 12 at a rather fast rate, which will be reduced as ports 130 and 114 close.

Movement through the midposition will be sustained by fluid entering port 131 and escaping through port 115. After the plunger 12 passes the midposition, port 130 will gradually open again to increase the rate of movement of the plunger. At the same time the tapered spool 150 will gradually open the pressure port 78 to start the return movement of the table at a gradually accelerated rate.

20 Thus, the pilot valve determines the deceleration of the table to stop; the time of movement of the reverse valve plunger to its mid-position determines the length of tarry of the table; and the rate of movement of the reverse valve plunger from its midposition to its end position determines the rate of acceleration of the table in its new direction.

25 The manner of reversing the table at the other end of its stroke is the same but this time the pilot valve plunger will be moving upward as viewed in Figure 8 and when the pressure port 97 is connected to port 98 the fluid will flow through the space 105 of the check valve 106 and the tarry valve 108 to the upper end of the reversing valve starting the plunger 12 on its downward movement. Fluid from the lower end of the valve will escape through channel 128' but due to the high resistance of the throttle valve 127, the pressure will rise, opening the check valve plunger 151 whereby the fluid will return to reservoir through channel 94.

30 During power operation of the table, interlock means have been provided for actuating the piston to disconnect the hand wheel 35 and, by referring to section 50 of the start and stop control valve, it will be noted that the plunger 44 is provided with an arcuate groove 152 which will be positioned to interconnect pressure port 153 to port 154, the latter being connected by channel 155 to the cylinder 41. Thus, whenever the valve plunger 44 is rotated counterclockwise to a running position, pressure is connected to the cylinder 41 to render the hand wheel 35 inoperative. When the plunger 44 is returned to a stop position the groove 152 will interconnect port 154 to an exhaust port 155' whereby the fluid in cylinder 41 may return to reservoir and permit operative engagement of the hand wheel 35 with the table rack 34.

35 Means have been provided for automatically feeding the grinding wheel toward the work at the end of each stroke of the table comprising a pick feed wheel 156, and a pick feed pawl 157 pivotally supported on the end of an oscillatable lever 158. This lever has gear teeth 159 on the periphery of its hub intermeshing with gear teeth 160 formed on the end of an oscillatable lever 161 that is pivotally supported at 162. A crank 163 operatively connected to the lever 161 has a roller 164 journaled in the end thereof for engagement by a contoured surface 165 formed on the periphery of a piston 166. The piston 166 is reciprocably mounted in a cylinder 167 which

has a port 168 at one end connected by channel 169 to port 170 of section 49 of the start and stop control valve, and a second port 171 in the other end connected by channel 172 to port 173 of section 51 of the start and stop control valve.

When the start and stop control valve is rotated to its running position the ports 170 and 173 are connected by cross bores 174 and 175 respectively to ports 176 and 177. These ports are connected by branch lines 178 and 179 to ports 99 and 98 respectively of the pilot valve whereby when these ports are alternately connected to pressure upon shifting of the pilot valve plunger, the piston 166 will be shifted first to one end of its cylinder and then to the other end of the cylinder. The contoured surface 165 has a peak 180 midway of the piston whereby upon movement of the piston from one end of its cylinder to the other, the crank 163 will be oscillated, thereby causing the pick feed pawl 157 to be ratcheted in one direction and caused to move the pick feed wheel during movement in the opposite direction.

Referring to Figure 2, the pick feed wheel 156 is supported for free rotation on shaft 181 which has a wheel 182 keyed thereto. The pick feed wheel is connectible with the hand wheel by retractable plunger 183. The shaft 181 has an eccentric 184 upon which is mounted a one-tooth differential gear 185 that serves to interconnect the shaft for rotation of internal gear 186. The hub of the internal gear is integrally connected to a pinion 187 which meshes with a gear 188 keyed to spline shaft 189. A spline sleeve 190 interconnects the spline shaft 189 with the splined end 191 of feed screw 192. The spline connection permits axial movement of the lead screw 192 with respect to the spline shaft 189.

The lead screw 192 is threaded in a nut 193 which is fixed with the cross slide 26. The rear end of the lead screw is provided with a piston 194 which is slidably mounted in a cylinder 195 which is attached to the frame 10 of the machine. It will now be evident that the pick feed wheel is operatively connected to cause rotation of the feed screw 192 and thereby effect small movements of the grinding wheel toward the work. Return movement of the grinding wheel is effected by withdrawing the plunger 183 and rotating the hand wheel 182 in an opposite direction. For purposes of rapidly withdrawing the grinding wheel an additional distance to facilitate work loading operations, a source of fluid pressure may be connected to cylinder 195 whereby the piston will directly pull the slide to a return position or on the other hand advance the slide to bring the grinding wheel adjacent the periphery of the work. The control mechanism for this hydraulic operation constitutes part of the control mechanism for effecting automatic infeed cycles of the grinding wheel without table traverse, and therefore, will be described in connection therewith, reference now being had to Figure 9.

The opposite ends of the cylinder 195 are connected by channels 196 and 197 to annular grooves 198 and 199 formed in the valve casing 200. This casing contains a servo-valve comprising an axially movable sleeve 201 reciprocably mounted in a bore 202 of the casing 200, and a valve plunger 203 reciprocably mounted within the sleeve. The plunger 203 has a feed back connection through the pivoted lever 204 from the lead screw 192. One end of the lever 204 is in position to be engaged by a shoulder 205

formed on the lead screw. The lever is held in this position against a stop 213 by means of a spring 206 which is interposed between a shoulder on the plunger 203 and a fixed plate 207. A second spring 208 is interposed between the plate 207 and the end of the sleeve 201 which thereby holds the sleeve into engagement with a bell crank 209, one end of the bell crank carrying a roller 210 which is held into contact with an internal cam surface 211 formed on the rotatable member 212.

The member 212 and associated cam are rotatable by the lever 213 in a clockwise direction as viewed in Figure 1 to cause counterclockwise rotation of the sleeve 201 to the right as viewed in Figure 9 to connect the pressure groove 214 to the groove 199 through the radial ports 215 in the sleeve, the annular groove 216 in the plunger 203 and the radial port 217 in the sleeve. This will result in fluid pressure flowing through channel 197 to one end of the cylinder 195, causing the piston 194 to advance the screw 192 and connected wheel slide toward the work at a fast rate. After the piston 194 has advanced to the piston shown in Figure 9 and taken up the lost motion between shoulder 208 and lever 204, the latter will be rotated to cause movement of the valve plunger 203 toward the right, thereby closing the radial ports 215 in the sleeve 201. The returning fluid from cylinder 195 flows through channel 196, annular groove 198, radial ports 218 in sleeve 201, annular groove 219 in plunger 203, radial ports 220 in sleeve 201 to the annular groove 221 in the valve block which is connected to the return channel 222. When the sleeve 201 is shifted in the other direction to connect the pressure groove 214 to groove 198, and thereby to the left end of the cylinder 195, the exhaust fluid will return through channel 197, groove 199, radial ports 217 in sleeve 201, annular groove 216 in plunger 203 and radial ports 223 in sleeve 201 to the exhaust line 222.

Attention is invited to the fact that the rotatable member 212 is connected by pinion teeth 224 and rack teeth 225 to a piston rod 226 which is integral with a piston 227 slidably mounted in a cylinder 228. When the piston 227 is in the extreme upper end of cylinder 228 which is the normal starting position, the lower end of the cylinder is full of fluid and due to the position of various valve mechanisms to be described later, this fluid is impounded in the cylinder which serves as means to prevent inadvertent rotation of the handle 213. Valve means have, therefore, been provided for operation by the lever 213 to connect the lower end of the cylinder to reservoir before the lever 213 can be rotated. This is accomplished by pivotally connecting the lever 213 by a pin 229 to the member 212, and additionally connecting the lever 213 by a link 230 to a by-pass valve plunger 231 whereby the lever must be pulled out, or rotated about the pin 229, to shift the plunger 231 into a fluid by-passing position before the lever can be rotated to effect actuation of the cam 211. A spring 232 is interposed between a shoulder 233 on the valve plunger and a fixed plate 234 for normally holding the parts in the position shown in Figures 3 and 9.

When the by-pass valve plunger 231 is in the position shown, a first annular groove 235 connects port 236, which receives fluid pressure from pump 60 through channel 237, to the upper port 238 of cylinder 228 through port 239 and

channel 240. A second annular groove 241 in the plunger connects the lower end of cylinder 228 to reservoir through port 242, channel 243, port 244, groove 241, port 245, channel 246 and port 247 of reversing valve 248. This valve has a plunger 249 which is normally held in the position shown by the spring 250 whereby an annular groove 251 in the plunger will interconnect port 247 to port 252. The latter port is connected by channel 253 to port 254 of an infeed rate throttle valve 255. This valve has a rotatable plunger 256 in which is cut a V-shaped resistance groove 257 through which fluid will flow to the return channel 258.

The resistance of this throttle valve is sufficient, however, to prevent escape of fluid from the lower end of cylinder 228 under the normal pressure which an operator would exert on the lever 213, and thus impounded fluid acts as means to prevent inadvertent rotation of the lever 213. The by-pass valve has another port 259 which is connected to the reservoir line 222 whereby when the lever 213 pulls the plunger 231 outward, this port registers with an annular groove 260 formed in the plunger. A cross bore 261 formed in this groove intersects an axial bore 262 which establishes communication with a second cross bore 263 formed in the annular groove 241. Thus, when the plunger is pulled out, ports 239 and 244 which are connected respectively to opposite ends of the cylinder 228 are directly connected to reservoir through the interdrilling in the plunger, thereby breaking the hydraulic lock on piston 227.

The operator may now rotate the cam 211 by lever 213 to open the servo-valve and effect the rapid movement of piston 194 in the manner explained. The manual movement of lever 213 is maintained until piston 227 has been moved downward a sufficient distance to uncover port 238. The operator then releases the lever 213 whereupon the spring 232 repositions the by-pass valve to effect interconnection of the pressure port 236 with port 239 whereby fluid pressure will continue the downward movement of the piston 227 and thereby continue rotation of the control cam 211. Since the port 242 at the lower end of the cylinder is now connected to the throttle valve 255 the rate of this continued movement will be determined by the setting of the throttle valve. Thus, the wheelhead is caused to execute a rapid positioning movement and then a slow controlled feed movement to effect grinding of the work.

The annular groove 199 of the servo-valve is connected by a channel 284 to port 265 of a headstock and tailstock control valve 266. This means that when the servo-valve sleeve 201 is initially shifted to the right as viewed in Figure 9 to connect the pressure source of annular groove 199 to cause infeeding movement of the grinding wheel that the plunger 267 of valve 266 will be forced upward under hydraulic pressure. This valve has a pressure port 268 which is normally connected by annular groove 288 to port 270 which has a channel 271 leading to tailstock operating cylinder 23. Pressure in this cylinder holds the tailstock center 19 in a retracted position. When the plunger 267 is forced upward the port 270 is disconnected from pressure and connected by the annular groove 272 to an exhaust port 273. This permits the oil in cylinder 23 to be exhausted to reservoir by the pressure of a spring 274 which continuously urges the tailstock center 19 forward to engage the work. 75

In addition, the valve 266 has a port 275 which is connected by channel 276 to a pressure operated switch 277 and in the normal position of the plunger 267 the port 275 is connected by annular groove 272 to the exhaust port 273. But upon upward movement of the plunger 267 the fluid pressure entering port 265 raises the plunger a sufficient distance to uncover port 275 whereby the pressure fluid will close the pressure operated switch 277 and start rotation of the headstock motor 15, which drives the face plate 16. Attention is invited to the fact that the port 270 leading from the tailstock operating cylinder is connected to the reservoir port 273 before the pressure port 265 is connected to port 275 so as to insure that the tailstock center has engaged the work before the headstock motor starts rotation thereof. In order to insure a little time delay between the happening of these two events a choke coil 278 is utilized to connect the upper end of the valve to the exhaust line 222. When the servo-valve is shifted in the other direction to connect the annular groove 199 to the exhaust port 223, a spring 279 assists in repositioning the plunger 267. It will be noted that in the downward movement of the plunger that the headstock pressure switch is opened before the tailstock center is retracted.

It will further be noted that the channel 276 has been indicated as provided with an extension 276' which can be coupled with conventional coolant or other controls not shown so that the same may be actuated by the hydraulic medium concurrently with the operation of the headstock switch.

As the piston 227 which causes operation of the servo-valve completes its downward movement, a pin 280 carried by the piston rod 226 rotates lever 281 which is connected to a pilot valve plunger 282 and shifts the plunger relative to a pressure port 283 in the valve housing 284.

The plunger 282 has an enlarged spool 285 which is movable relative to the pressure port 283 whereby after the spool passes the pressure port the incoming pressure fluid produces a pressure differential action which completes the shifting movement of the plunger. When the plunger is in the position shown in Figure 9 an exhaust port 286 is connected to port 287 by annular groove 288 in the plunger whereby the end of an interlock cylinder 289 containing an interlock plunger 290 is connected to reservoir through channel 291 which is connected to the port 287. The interlock plunger 290 engages a groove 291 formed in the start and stop valve control plunger 44, and, in the position shown, prevents rotation of this plunger to a table traversing position by the lever 42. The spring 292 holds the interlock plunger in the position shown.

When the pilot valve plunger is shifted upward the pressure from port 283 is connected by the annular groove 288 to port 287, thereby effecting withdrawal of the plunger 290. This permits the operator to rotate the lever 42 into a running position to effect a traversing movement of the table 13 by power if such movement is desired.

The upward shifting of the pilot valve plunger also effects interconnection of ports 293 and 294 by annular groove 295. The port 293 is connected by a channel 296 to port 297 of a tarry valve 298. This valve has a pressure port 299 and a rotatably adjustable plunger 300 which has a V-shaped groove 301 cut in its periphery for

varying the rate of flow from port 299 to port 291.

The port 294 of the pilot valve is connected by a channel 302 to port 303 located in the lower end of the reversing valve housing whereby fluid pressure will slowly flow through the throttle valve 298 to the reversing valve housing, causing a slow upward movement of the reversing valve plunger 249.

When the annular groove 251 in the reversing valve plunger 249 has moved sufficiently to interconnect pressure port 304 to port 247, pressure fluid will then flow to the lower end of cylinder 228 through interconnected ports 245 and 244 of the by-pass valve and channel 243. The piston 227 will now start to move upward, rotating the control cam of the servo-valve in the opposite direction to cause retraction of the wheel head. Although port 238 at the upper end of cylinder 228 is still connected to pressure the piston 227 will still move upward due to the fact that the area of the lower end of the piston 227 is greater than the area of the upper end. When the piston closes port 238 it traps fluid in the upper end of the cylinder. However, a port 305 located in the cylinder is now in communication with a port 306 contained in the piston. The port 306 is connected by an interdrilled passage 307 to the upper face of the piston 227 whereby the entrapped fluid may still escape to the reservoir line 94 whereby the piston may continue its movement to return control lever 213 to its starting position.

As the piston 227 completes its upward movement the pin 280 carried by the piston rod 226 rotates the pilot valve trip lever 281 in a clockwise direction, thereby shifting the pilot valve plunger 282 downward into the position shown.

This reconnects the interlock cylinder 289 with reservoir whereby the spring 292 may reposition the interlock plunger 290 into engagement with the start and stop valve control plunger 44. It also connects port 294, leading from the lower end of the reversing valve housing, to reservoir through an axial passage 308 in the pilot valve, which has cross bores 309 and 310 communicating with annular grooves 295 and 311 respectively. The annular groove 311 is moved into communication with exhaust port 312 when the plunger 282 has completed its downward shifting movement. This permits the reversing valve plunger 249 to be returned by the spring 250, thereby disconnecting the pressure port 304 from port 247 so that pressure fluid no longer flows to the lower end of cylinder 228, and reestablishes the connection between ports 247 and 252 whereby the lower end of cylinder 228 is connected through the throttle valve 258 preparatory to control the rate of the next infeeding movement.

Attention is invited to the fact that at any time during automatic infeeding of the grinding wheel, the operator may, at will, interrupt the infeed cycle and effect immediate retraction of the grinding wheel by pulling out the lever 213, which will immediately interconnect the upper and lower ends of the cylinder 228. Rotation of the lever back to its starting position will manually return the piston 227 to its starting position due to the mechanical interconnection between the lever 213 and the piston.

This movement will simultaneously return the control cam 211 so that the servo-valve sleeve 201 will be positioned sufficiently to the left to

cause full retraction of the wheel head. It is to be remembered that although the wheel head has a total movement of approximately one inch the greater part of this movement is effected at a rapid traverse rate because the servo-valve is only effective during the last $\frac{1}{2}$ " movement. The servo-valve plunger 203 is urged by a spring 206 in one direction and a stop 313 is provided for limiting this movement. Therefore, when the parts are in a starting position the pressure port 215 is connected to the annular groove 198 and thereby to the cylinder 195 because the stop 313 limits the plunger 213 from shifting a sufficient distance to close the pressure port 215.

This means that after the slide has returned $\frac{1}{2}$ " and the lever 204 has engaged the stop 313, the wheelhead continues its retraction automatically until the piston 194 engages the end of its cylinder. The same thing is true on the advancing movement in that after the cam has been rotated to effect sufficient displacement of the sleeve 201 to connect the pressure port 215 to the annular groove 199 the wheel head slide moves in at a rapid traverse rate until the shoulder 205 on the lead screw picks up the lever 204 and thereby establishes the feed back connection to the servo-valve, after which the rate of movement is determined by the infeed throttle valve.

It will now be evident that the control cam 211 can only control the last $\frac{1}{2}$ " of the total inward movement of the wheel head.

The operator pulls out the lever 213 and rotates it sufficiently to start the wheel head moving in. If the operator stops rotation of the lever 213 as soon as the wheel head starts to move, the wheel head will continue its inward movement for almost an inch automatically because the co-operating parts of the servo-valve have been positioned to connect the fluid pressure to the rear end of the cylinder and nothing can occur to stop this flow until the shoulder 205 on the lead screw picks up the feed back lever 204 and repositions the plunger 203. At this time the piston 227 will have moved a sufficient distance to uncover the port 238 and if the operator releases the lever 213, the spring 232 will reposition the by-pass valve plunger to connect pressure to port 238 and thereby continue the movement of the wheel head through its last $\frac{1}{2}$ " of movement at a slow grinding rate.

It is well known to those skilled in the art that the amount of stock left on a work piece to be ground off to produce the final size of the work varies considerably which is in part determined by the number and character of the preceding operations upon the work before it reaches the grinding machine. It should, therefore, be evident that if only .010" stock were left in the work and the machine was provided with a fixed movement of $\frac{1}{2}$ " for automatic infeed that considerable time would be wasted and the production of the machine seriously decreased.

Provision has therefore, been made whereby the operator may determine the limit of the rapid traverse movement or in other words, increase the length of the rapid traverse movement so that when the slow feeding movement becomes effective the grinding wheel will be approximately in engagement with the work and no time will, therefore, be lost.

This is accomplished by providing an adjustable stop member for the control lever 213 and reference may now be had to Figures 3, 5 and 6.

This stop is indicated by the reference numeral 314 and as shown in Figures 3 and 6, it is pivotally supported by a pin 315 on a rotatably adjustable plate 316. The plate is provided with a rectangular annular rib 317 which is held in a rectangular guideway 318 by a plate 319. Rotation of the plate is effected by a fixed worm 320 engaging a worm wheel 321 which is fastened to the plate. The worm 320 is pinned to a shaft 322 which is journaled in the housing 323 and provided with an operating knob 324. The plate 316 is provided with graduations 325 which are movable with respect to a fixed arrow 326. The stop 314 is normally held in a projected position by a spring pressed ball 327 whereby the end of the stop lies in the plane of rotation of the lever 213 when the same has been pulled out by the operator. By suitably marking the graduations 325 to indicate the amount of stock to be removed by the grinding wheel, the stop 314 may be positioned to limit the movement of the lever 213 so that when the operator rotates the lever into engagement with the stop, contact will just be established between the grinding wheel and the work. This means that the piston 227 may be moved at a rapid traverse rate a considerable distance beyond the port 238 before the slow in-feeding movement starts. It will be obvious that as soon as the operator releases the lever 213 after engagement with the stop 314 the lever will move laterally out of engagement with the stop, thus clearing the same so that the remainder of the movement may be completed. The stop has been pivotally mounted so that in case the lever is pulled out by the operator at any time to return the parts the lever will simply rotate the stop out of the path of the lever during its return movement. When the machine is utilized for traverse grinding the stop is set at zero so that the lever 213 may rotate a full stroke and thus bring the wheel head in the full distance allowed by cylinder 195. In addition, the tarry valve 298 is completely closed so that the reversing valve will not be operated whereby the piston 194 will be held at the forward end of its cylinder. The in and out movement of the grinding wheel will then be effected by the pick feed mechanism through rotation of the screw 192. Since the pilot valve 283 will now be in a position to connect pressure port 283 to port 287 the plunger 290 will be held in a retracted position so as not to interfere with the actuation of the start and stop control valve.

A yieldable stop shown in Figure 10 has been provided for determining the stop position of the start and stop control lever 42 whereby in an emergency during traverse grinding the operator may throw the lever 42 to its "stop" position to stop the table and by applying sufficient pressure the lever may continue its rotation beyond the stop position to effect retraction of the wheel head by the piston 194. This is accomplished by providing the plunger 44 with a cross bore 329 as shown in section 52 of the valve. This section is provided with a pressure port 330 which may be connected by the cross bore to port 331, the latter being connected by a channel 332 to channel 302 which interconnects port 294 of the pilot valve with port 303 of the reversing valve. This means that pressure fluid will flow to port 303 of the reversing valve and shift the reversing valve plunger 249 upward to connect the pressure port 304 to port 247 and thereby, through the by-pass valve to the lower end of cylinder 228, causing

upward movement of the piston 227 and rotation of the servo-valve control cam to its starting position. This will cause immediate retraction of the wheel head.

5 The yieldable stop comprises a stop member 333 which is pivotally supported on a fixed pin, 334, and held against clockwise rotation by a spring 335 by a stop pin 336. The rotatable plunger 44 carries a cross pin 337 which abuts the nose 338 of the stop 333 when rotated to a stop position. Further movement will rotate the yieldable stop in a counter-clockwise direction. Upon release of lever 42 the parts will return to a stop position.

15 In the hydraulic diagrams, the pump supply channel is indicated throughout by the reference numeral 59, and the reservoir return channel by the number 94. The channel 59 has a suitable pressure relief valve 339 connected thereto as shown in Figure 8 to protect the system. There is also shown a control valve 340 which may be utilized for controlling power operation of a coolant supply valve.

20 In the position shown in Figure 8 this valve derives pressure for actuation of the coolant supply valve or the like through conduit 341, groove 342 and conduit 343 from the start-stop valve as indicated in sections 47 and 48. Alternatively, however, if the control button 344 is pulled outward, the coolant or other devices controllable by pressure in the conduit 345 derive this pressure from the main pressure conduit system 59 and the connection between 341 and 345 is shut off by spool portion 346 of said valve.

25 35 There has thus been provided an improved grinding machine having novel traversing mechanism for the table and improved mechanism for in-feeding the grinding wheel, together with suitable interlocks between the two mechanisms 40 rendering the machine safe for operation by comparatively inexperienced operators.

What is claimed is:

1. In a grinding machine having a grinding wheel support and a work support, the combination of power operable means for moving one of said supports toward and from the other support including a fluid operable motor connected for actuation of one of said supports, a control valve therefor, a rotatable cam for actuating 45 said valve, a piston actuator for said cam, means for hydraulically locking said piston against movement, a manual control lever, means operable by said lever upon movement in one direction for releasing the locking fluid, means operable by said lever upon movement in a second direction to effect simultaneously movement of the piston and cam to initiate movement of said slide, and means controlled by the lever for connecting fluid pressure to said piston after a predetermined movement thereof whereby said piston will automatically continue actuation of the motor.

2. In a grinding machine having a grinding wheel support and a work support, the combination of power operable means for moving one of said supports toward and from the other support including a fluid operable motor connected for actuation of one of said supports, a servo-control valve for the motor, a rotatable cam for actuating said servo-valve, a piston actuator for said cam, means for hydraulically locking said piston against movement, a manual control lever, means operable by said lever upon movement in one direction for releasing the locking fluid, means operable by said lever upon movement in

a second direction to effect simultaneously movement of the piston and cam to initiate movement of said slide, means controlled by the lever for connecting fluid pressure to said piston to continue the infeeding movement of said slide by power, means trip operable by the piston for automatically reversing its direction of movement, and means to produce a delay in effecting said reversal whereby a dwell in the movement of the slide will be created to permit the grinding wheel to finish the work to size.

3. In a grinding machine having a grinding wheel support and a work support, the combination of power operable means for effecting movement of one of said supports toward and from the other including a control cam for said power means, a fluid operable piston operatively connected for effecting rotation of said cam, a hydraulic control circuit for said piston including a source of pressure and a reversing valve, a throttle valve, means in the reversing valve for directly connecting the source of pressure with one side of said piston and serially connecting said source of pressure through said throttle valve to the other side of said piston whereby said piston will move at a slow rate in one direction to effect advancing movement of said support and at a rapid traverse rate to effect return movement of said support, means hydraulically locking said piston at the completion of the return stroke, a starting lever, and means operable by said lever for releasing the locking fluid to initiate the next cycle.

4. In a grinding machine having a grinding wheel support and a work support, the combination of power operable means for feeding one of said supports toward and from the other support including a rotatable element operatively connected for controlling said movement in accordance with the rate of movement of said element, a fluid operable piston for power moving said element, a cylinder containing said piston, said cylinder having a first port for receiving fluid to cause one direction of movement of said piston and a second port for receiving fluid for causing a return movement of said piston, said first port being positioned so as to be closed by said piston when in a starting position, manually operable means for moving said piston a sufficient distance to uncover said first port and simultaneously effect a positioning movement of said support, and additional means operable by said manual control means to connect pressure to the first-named port to continue the movement under control of said element.

5. In a grinding machine having a grinding wheel support and a work support, the combination of means for effecting movement of one of said supports toward and from the other including a prime mover, a movable rate control means having a stop position, a manually operable control lever for shifting said rate control means to cause actuation of the movable support, power operable means for continuing the movement of said rate control means, said power operable means including a piston, a cylinder, a piston rod connecting the piston for movement of said rate control means, a source of pressure for actuating said piston, said piston having a hydraulically inoperative position, and means controlled by the lever for moving said piston to a hydraulically operative position and sequentially connecting fluid pressure to the cylinder to continue movement of the piston.

6. In a machine tool having a grinding wheel support and a work support, the combination of power operable mechanism for effecting movement of one of said supports toward the other support including a hydraulic control circuit, a manually operable control lever having a stop position in which the control circuit is hydraulically locked, means to shift said lever in one direction to unlock said circuit, means responsive to movement of the lever in the second direction to effect a rapid positioning movement of the support, and an adjustable stop for said lever for determining the length of said positioning movement.

15 7. In a machine tool having a grinding wheel support and a work support, the combination of power operable mechanism for effecting movement of one of said supports toward the other support including a hydraulic control circuit, a manually operable control lever having a stop position in which the control circuit is hydraulically locked, means to shift said lever in one direction to unlock said circuit, means responsive to movement of the lever in a second direction to effect a rapid positioning movement of the support, an adjustable stop for said lever for determining the length of said positioning movement, and graduated means for micrometrically setting said stop.

20 8. In a grinding machine having a grinding wheel support and a work support, the combination of power operable means for effecting relative movement between said supports, control means for said power operable means including a lever rotatable in one plane for effecting a rapid traverse movement of said support, a stop for said lever for determining the extent of said rapid traverse movement, said lever being shiftable into a second plane to clear said stop, means operable by the last-named movement of said lever to effect power rotation thereof in a second plane to produce a feeding movement of said support.

25 9. In a grinding machine having a grinding wheel support and a work support, the combination of a hydraulic operating circuit for traversing the work support including a start and stop control valve, a second hydraulic operating circuit for feeding the grinding wheel support toward and from the work support including a direction determining valve, an interlock plunger, means normally holding said plunger in engagement with the first-named valve to prevent movement thereof from its stop position, and fluid operable means controlled by said direction determining valve for withdrawing said interlock after the grinding wheel has completed its power movement toward the work support.

30 10. In a grinding machine having a grinding wheel support and a work support, the combination of a fluid operable control circuit for advancing said grinding wheel support toward the work support, said circuit having a reversing valve which is fluid shiftable to effect retraction of said support, a fluid operable control circuit for traversing said support including a control valve normally movable between a stop position and a running position to control the traversing movement of said work support, a control lever for said valve, a resilient stop for limiting movement of the lever when it reaches a stop position, and means in the valve and responsive to movement of the lever beyond its stop position to connect fluid pressure to said reversing valve whereby a continuous unidirectional movement 35 of said control lever will stop the work support

and effect retraction of the grinding wheel support.

11. In a grinding machine having a grinding wheel support and a work support, means for controlling relative movement of said supports including a piston and cylinder mechanism providing a hydraulic motor, a source of hydraulic actuating medium, a servo-control mechanism for determining the rate and direction of flow of the hydraulic medium with respect to the motor, said servo-mechanism including a pair of relatively adjustable parts, control means for determining the amount and direction of movement of one of said servo-parts, and a feed back mechanism including a lost motion connection between the hydraulic motor and the other of said servo-elements whereby an initial rapid movement of the motor may be effected by shifting of the first servo-element prior to the counteracting movement of the other element as effected through said lost motion connection.

12. In a grinding machine having a grinding wheel support and a work support, means for controlling relative movement of said supports including a piston carried by one of the supports and a containing cylinder for the piston carried by the other of said supports, a source of hydraulic actuating medium, and means for controlling the activation of the piston and cylinder elements by the hydraulic medium including a servo-mechanism having a first element shiftable for operatively coupling the hydraulic medium with the cylinder, a second element shiftable to counteract the movement of the first, a feed back from the hydraulic motor to said second element for determining the positioning thereof, said feed back including a lost motion connection permitting limited actuation of the motor without actuation of the second element of the servo, a retractable tailstock carried by the work support, a rotatable headstock carried by the work support, means for activating said elements including hydraulic controls and hydraulic connections establishable by movement of the first servo-element prior to actuation of the lost motion feed back whereby the tailstock and headstock will be activated prior to initiation of the servo-control of relative movement of the supports.

13. In a grinding machine, the combination with a work support and a tool support, of means for controlling the relative movement of the supports including a hydraulic motor having a cylinder portion carried by one of the supports and a piston and piston rod operatively associated with the other of the supports and a hydraulic control circuit for operation of the motor including a source of hydraulic actuating medium and a servo-device intervening the source of medium and the motor, said servo-device including a first valve portion shiftable to couple the medium with the cylinder, a second counteracting valve portion shiftable in opposition to the first, cam means for effecting shifting of the first valve member, a linkage including a lost motion device connecting the second valve member with the hydraulic motor to initiate feed back actuation of the servo-mechanism upon prescribed movement of the hydraulic motor.

14. In a grinding machine, the combination with a work support and a tool support, of means for controlling the relative movement of the supports including a hydraulic motor having a cylinder portion carried by one of the supports and a piston and piston rod operatively associated

with the other of the supports and a hydraulic control circuit for operation of the motor including a source of hydraulic actuating medium and a servo-device intervening the source of medium and the motor, said servo-device including a first valve portion shiftable to couple the medium with the cylinder, a second counteracting valve portion shiftable in opposition to the first, cam means for effecting shifting of the first valve member, a linkage including a lost motion device connecting the second valve member with the hydraulic motor to initiate feed back actuation of the servo-mechanism upon prescribed movement of the hydraulic motor, a first resilient means to reversely actuate the feed back servo-element, and means for limiting the extent of resultant actuation thereof.

15. In a grinding machine, the combination with a work support and a tool support, of means for controlling the relative movement of the supports including a hydraulic motor having a cylinder portion carried by one of the supports and a piston and piston rod operatively associated with the other of the supports and a hydraulic control circuit for operation of the motor including a source of hydraulic actuating medium and a servo-device intervening the source of medium and the motor, said servo-device including a first valve portion shiftable to couple the medium with the cylinder, a second counteracting valve portion shiftable in opposition to the first, cam means for effecting shifting of the first valve member, a linkage including a lost motion device connecting the second valve member with the hydraulic motor to initiate feed back actuation of the servo-mechanism upon prescribed movement of the hydraulic motor, a first resilient means to reversely actuate the feed back servo-element, and means for limiting the extent of resultant actuation thereof.

16. In a grinding machine, the combination with a work support and a tool support, of means for controlling the relative movement of the supports including a hydraulic motor having a cylinder portion carried by one of the supports and a piston and piston rod operatively associated with the other of the supports and a hydraulic control circuit for operation of the motor including a source of hydraulic actuating medium and a servo-device intervening the source of medium and the motor, said servo-device including a first valve portion shiftable to couple the medium with the cylinder, a second counteracting valve portion shiftable in opposition to the first, cam means for effecting shifting of the first valve member, a linkage including a lost motion device connecting the second valve member with the hydraulic motor to initiate feed back actuation of the servo-mechanism upon prescribed movement of the hydraulic motor, means for normally locking the cam against movement, and a control lever mounted for oscillation in one direction to effect a release of the cam and for oscillation in an angularly related direction for effecting rotation of the cam to actuate the valve member.

17. In a grinding machine, the combination with a work support and a tool support, of means for controlling the relative movement of the supports including a hydraulic motor having a cylinder portion carried by one of the supports and a piston and piston rod operatively associated with the other of the supports and a hydraulic control circuit for operation of the motor in-

cluding a source of hydraulic actuating medium and a servo-device intervening the source of medium and the motor, said servo-device including a first valve portion shiftable to couple the medium with the cylinder, a second counteracting valve portion shiftable in opposition to the first, cam means for effecting shifting of the first valve member, a linkage including a lost motion device connecting the second valve member with the hydraulic motor to initiate feed back actuation of the servo-mechanism upon prescribed movement of the hydraulic motor, means for normally locking the cam against movement, a control lever mounted for oscillation in one direction to effect a release of the cam and for oscillation in an angularly related direction for effecting rotation of the cam to actuate the valve member, and a hydraulic motor coupled with the cam and energizable by one of said lever movements for effecting power actuation of the cam.

18. In a grinding machine, the combination with a work support and a tool support, of means for controlling the relative movement of the supports including a hydraulic motor having a cylinder portion carried by one of the supports and a piston and piston rod operatively associated with the other of the supports and a hydraulic control circuit for operation of the motor including a source of hydraulic actuating medium and a servo-device intervening the source of medium and the motor, said servo-device including a first valve portion shiftable to couple the medium with the cylinder, a second counteracting valve portion shiftable in opposition to the first, cam means for effecting shifting of the first valve member, a linkage including a lost motion device connecting the second valve member with the hydraulic motor to initiate feed back actuation of the servo-mechanism upon prescribed movement of the hydraulic motor, means for normally locking the cam against movement, a control lever mounted for oscillation in one direction to effect a release of the cam and for

oscillation in an angularly related direction for effecting rotation of the cam to actuate the valve member, a hydraulic motor coupled with the cam and energizable by one of said lever movements for effecting power actuation of the cam, and means for adjustably determining the rate of power actuation of said cam.

19. In a grinding machine, the combination with a work support and a tool support, of means for controlling the relative movement of the supports including a hydraulic motor having a cylinder portion carried by one of the supports and a piston and piston rod operatively associated with the other of the supports and a hydraulic control circuit for operation of the motor including a source of hydraulic actuating medium and a servo-device intervening the source of medium and the motor, said servo-device including a first valve portion shiftable to couple the medium with the cylinder, a second counteracting valve portion shiftable in opposition to the first, cam means for effecting shifting of the first valve member, a linkage including a lost motion device connecting the second valve member with the hydraulic motor to initiate feed back actuation of the servo-mechanism upon prescribed movement of the hydraulic motor, means for normally locking the cam against movement, a control lever mounted for oscillation in one direction to effect a release of the cam and for oscillation in an angularly related direction for effecting rotation of the cam to actuate the valve member, a hydraulic motor coupled with the cam and energizable by one of said lever movements for effecting power actuation of the cam, means for adjustably determining the rate of power actuation of said cam, trip operated means for effecting a reversal of the hydraulic support actuating motor, and additional means for effecting said reversal irrespective of the position of said trip operable means.

JACOB DECKER.
HANS ERNST.
